E. G. GARTIN

BRAKING MECHANISM

Filed March 21, 1921

Inventor:
Elmer G. Gartin.
by
Atty.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

BRAKING MECHANISM.

Application filed March 21, 1921. Serial No. 454,103.

My invention relates to braking mechanisms and more particularly to braking mechanisms for use in connection with feeding mechanisms of the fluid pressure type.

5 An object of my invention is to provide an improved braking mechanism. Another object of my invention is to provide an improved braking mechanism for use in controlling the rate of feed of a feeding mechanism. A further object of my invention is to provide an improved braking mechanism for use in connection with that type of fluid pressure feeding mechanisms used with drilling motors. A still further object of 10 my invention is to provide an improved braking mechanism for controlling the rate of feed of that type of drill motor known as a stoper. Other objects of my invention will appear in the course of the following 15 specification and appended claims.

In the accompanying drawings, I have shown for purposes of illustration, one form which my invention may assume in practice.

In these drawings,

25 Fig. 1 is a central longitudinal section through the feed cylinder of a drill motor in which is incorporated the illustrative form of my improved braking mechanism.

Fig. 2 is a transverse section on the line 30 2—2 of Fig. 1.

For purposes of illustration I have disclosed the illustrative embodiment of my improved braking mechanism used in controlling the feed of a rock drill of the type known as a stoper. In drills of this type a percussive motor, whose rear end is illustrated at 1, is fed by fluid pressure feeding mechanism generally indicated by 2. The feeding means comprises a cylinder 3 having a bore 4 in which a piston generally indicated by 5 is reciprocable.

The piston 5 herein is provided with a piston rod 6 which is in the present case of hollow construction having a bore 7 therein. 45 The piston rod passes through a bushing 8 closing the rear end of the bore 4 of the cylinder 3 and is provided at its lower end with a pointed projection 9 adapted to engage the rock or some other suitable abutment during drilling operation. Fluid pressure is admitted in a well known manner under the control of the valve 10, which also controls by well known port means (not shown) the motor 1, by way of a passage 50 11 to the front end of the cylinder where it

acts upon the piston 5 to force the cylinder forwardly with respect to the piston which is held stationary by reason of its abutment against the rock or other stationary support. The piston 5 is of multi-part construction 60 and comprises a member 12 provided with an annular groove 13 in its periphery, in which groove a pair of substantially semi-circular brake applying members 14 are provided, these being in turn provided with plungers 15 which extend radially and which project at their inner ends into a cylindrical bore 16 extending longitudinally through the piston 5. The piston also comprises a packing securing ring 17 holding a 70 cup packing 18 of well-known form between it and the portion 12 of the piston. Surrounding the members 14 and disposed in the groove 13 is a split band of friction material 20 which, when forced outward by 75 the members 14, frictionally engages the bore 4 of the cylinder and tends to retard the relative movement of the cylinder with respect to the piston. Suitable packings 19 surround the plungers 15 and tend to prevent 80 air passing behind the members 14 and forcing the friction material into engagement with the cylinder bore.

Extending longitudinally within the bore 7 of the piston rod 6 is a member 21 which is generally elliptical in cross section and which is provided at its rear end with a guide head 22 substantially fitting the bore 7 of the piston rod. This member 22 is provided with ports 23 to permit fluid pressure to pass to the opposite sides thereof. The member 21 extends through the bore 16 formed on the piston and at its forward end is slightly reduced in diameter and turned to circular shape as indicated at 25, thereby 90 providing a shoulder 24 which engages against a stationary shoulder 26 surrounding the portion 25. A suitable packing 27 surrounds the portion 25 of the member 21 and prevents leakage of air out of the forward end of the cylinder. The reduced portion 25 of the member 21 is made polygonal at its forward end and a suitable handle 28 projecting through a slot 29 in the side wall of a chamber 30 interposed between the front 100 end of the feed cylinder and the rear end of the motor 1 is attached to the polygonal portion of the member 21.

It will be noted from an inspection of Fig. 2 that, when the member 21 lies in such 110

relation to the plungers 15 that its minor axis is in alinement with the axes of these plungers, the plungers do not force out the packing in frictional contact with the bore 4 of the cylinder and accordingly the cylinder is free to move in respect to the piston without braking action. When, however, the handle 28 is turned in either direction from its position shown in Figs. 1 and 2, it will be evident that the member 21 acts as a cam and that irrespective of the position of the feed cylinder relative to the piston, the plungers 15 will be forced outwardly and the packing material 20 will frictionally engage the bore 4 of the cylinder 3 and will tend to retard the relative movements of cylinder and piston. It will be obvious that, if desired, a suitable latch and segment rack of well-known construction may be employed with the handle 28 in order to fix it in any desired position in the groove 29 so that a substantially constant friction between the packing material 20 and the bore 4 may be maintained. Such mechanism is shown at 34.

It will be obvious that the piston rod 6 must be maintained in unvarying relation, as respects rotation, to the cylinder 3 and accordingly I have provided, by brazing, riveting, or any suitable means, a spline 30 extending longitudinally thereof and engaging in a groove 31 formed in the closure bushing 8 at the rear end of a cylinder 3. The usual vent 33 is provided in the wall of the cylinder 3, and any air which gets behind the packings is permitted to escape to a space communicating with this vent by ports 32.

From the foregoing description it will be obvious that I have provided braking mechanism of a type which is very convenient to operate in that the control lever is mounted at one end of the cylinder and in fixed relation to the throttle valve 10 whereby the operator may readily move his hand between the control means used in the operation of the drill. It will also be obvious that by reason of the improved construction, the efficiency of the braking means does not vary from point to point of the cylinder, but that the connection provided is such as to permit the control of the brake irrespective of the relative positions of piston and cylinder.

While I have in this application specifically described one form which my invention may assume in practice, it will be understood that this form of the same is used for purposes of illustration and that the invention may be embodied in various other forms without departing from its spirit or the scope of the appended claims.

What I claim as new and desire to secure by Letters Patent is:

1. Feeding mechanism comprising, in com-

bination, stationary and movable members cooperating to form an expansible chamber feeding motor, means carried by one of said members and frictionally engageable with the other, and means carried by the other of said members for controlling said frictional engaging means.

2. Feeding mechanism comprising, in combination, relatively stationary and movable members cooperating to form an expansible chamber feeding motor, means carried by one of said members and frictionally engageable with the other to retard such relative movement, and means carried by the other of said members for mechanically controlling said frictional engaging means.

3. Feeding mechanism comprising, in combination, stationary and movable members cooperating to form an expansible chamber feeding motor, braking means carried by the stationary member, and means for controlling the braking means carried by the movable member.

4. Feeding mechanism comprising in combination, stationary and movable members cooperating to form an expansible chamber feeding motor, braking means for said movable member carried by said stationary member, and controlling means for said braking means bodily translatively movable relative to said braking means during operation of the feeding mechanism, said controlling means being operative to control said braking means irrespective of the position thereof relative thereto.

5. Feeding mechanism comprising, in combination, a stationary member, a member movable relative thereto, said members cooperating to form an expansible chamber feeding motor, a member carried by the stationary member and adapted frictionally to engage the moving member, and a cam means carried by the movable member for rendering effective the frictional engaging means.

6. Feeding mechanism comprising, in combination, a stationary member, a member movable relative thereto, said members cooperating to form an expansible chamber feeding motor, a member carried by the stationary member and adapted frictionally to engage the moving member, and relatively rotatable means carried by the movable member for rendering effective the frictional engaging means.

7. Braking means comprising, in combination, a stationary member, a movable member, said members cooperating to form an expansible chamber feeding motor, frictional braking means carried by the stationary member, operating means for the frictional braking means carried by the movable member and disposed within the periphery of the stationary member, and means for controlling the operating means.

8. Feeding mechanism comprising, in combination, a cylinder, a piston therein, means carried by the piston for frictionally engaging the bore of the cylinder, means including an element extending longitudinally through the piston for rendering said frictional engaging means operative, and controlling means for said last mentioned means.

9. Feeding mechanism comprising, in combination, a cylinder, a piston therein, means carried by the piston for frictionally engaging the bore of the cylinder, means extending longitudinally through the piston for rendering said frictional engaging means operative, and controlling means for said last mentioned means carried by the cylinder.

10. Feeding mechanism comprising, in combination, a cylinder, a piston therein, means carried by the piston for frictionally engaging the bore of the cylinder, and means extending longitudinally through the piston for rendering said frictional engaging means operative rotatable about an axis parallel to a line parallel to the axis of said cylinder.

11. Braking means comprising, in combination, a stationary piston, a cylinder movable relative thereto, frictional means surrounding the periphery of said piston and adapted to engage the bore of the cylinder, means for pressing said frictional means into braking engagement with the bore of the cylinder comprising brake applying means, cam means cooperating therewith and extending through the piston, and means for controlling the last mentioned means.

12. Feeding mechanism comprising, in combination, a cylinder, a piston therein, a brake band carried by one of said members, means for directly applying said brake band carried by said last mentioned member, and means carried by the other of said members for causing operation of said brake band applying means, said means being coaxially arranged with both of said members.

13. Feeding mechanism comprising, in combination, a movable cylinder movable to effect feeding of the device to be fed, a stationary piston, and radially expandible means carried by said piston for restraining the movement of said cylinder.

14. Feeding mechanism comprising in combination, cooperating relatively longitudinally movable elements cooperating to

form an expandible chamber feeding motor, and cam operated means for controlling the movement thereof, said means being located within one of said elements and having controlling means therefor carried by the other element.

15. Feeding mechanism comprising, in combination, a cylinder and a piston having relative movement, and cam operated means carried by said piston for restraining movement of said cylinder.

16. Feeding mechanism comprising, in combination, a movable cylinder movable during feed with the device to be fed having a bore formed therein, a stationary piston disposed in said bore, and means for frictionally engaging the surface of said bore for restraining movement of said cylinder.

17. Feeding mechanism comprising, in combination, stationary and movable members cooperating to form an expandible chamber feeding motor, radially expanding braking means carried by said stationary member, and means carried by said movable member for varying the capacity of the radially expanding braking means.

18. Feeding mechanism comprising, in combination, a stationary member and a movable member cooperating to form an expandible chamber feeding motor, means carried by said stationary member for frictionally engaging said movable member, and controlling means carried by said movable member for applying said frictional means.

19. In a drilling mechanism, in combination, a drilling motor, pressure fluid feeding means therefor including a movable cylinder and a stationary piston, means for controlling the pressure fluid supply thereto, means carried by said piston for restraining the movement of said cylinder, and means movable with said cylinder for varying the capacity of said feed restraining means.

20. In a drill mechanism, in combination, a drilling motor, pressure fluid feeding means therefor including a stationary and a movable member, restraining means for said feeding means carried by said stationary member, and means movable with said drilling motor for controlling the pressure fluid supply of the feeding means and the capacity of the feed restraining means.

In testimony whereof I affix my signature.

ELMER G. GARTIN.
